CLIP FOR MOUNTING ROTATABLE ANTENNA
ON RECEIVER CABINET, THE CLIP HELD SE-
CURE BY OUTWARD FORCES EXERTED BY
RESILIENT CLIP ARMS

William L. Arrington, Roselle, Ill., assignor to Admiral Corporation, Chicago, Ill., a corporation of Delaware
 Filed July 1, 1964, Ser. No. 379,478
 8 Claims. (Cl. 343—702)

This invention relates to antenna clips. Specifically, it relates to removable antenna clips for mounting antennae to receiver cabinets. The invention can be used in a number of environments but will be described in the environment of a television cabinet upon which is mounted a rotatable telescopic antenna of the type which has a spherical base and tubular antenna elements extending from said base.

In order that an antenna clip effectively mount a rotatable antenna to a television cabinet, the clip must contain certain elements. These elements include bearing surfaces to position the spherical base of the antenna, means allowing the antenna elements to extend outside of the cabinet, means for biasing the bearing surfaces towards each other so that the spherical ball will remain positioned between the bearing surfaces but will be free to undergo limited rotational motion, and means for securing the clip within the cabinet.

The invention discloses an improved antenna clip wherein a single metal stamping is used to mount an antenna to a television cabinet and also to secure itself to the cabinet by engaging the cabinet with means independent of the means positioning the antenna.

Consequently, it is an object of this invention to provide an improved antenna clip.

Another object of this invention is to provide an improved antenna clip which is economical in its manufacture.

Still another object of the invention is to provide an antenna clip which can be easily inserted into and withdrawn from a television cabinet.

A further object of the invention is to provide an improved antenna clip which will securely mount an antenna to a television cabinet and also secure itself to the television cabinet.

Other objects of the invention will become apparent to those skilled in the art upon reading the specification in conjunction with the drawing in which:

FIGURE 1 is a perspective view of an antenna clip constructed in accordance with the invention.

FIGURE 2 is a side view of an antenna clip constructed in accordance with the invention.

FIGURE 3 is a partial side view of a portion of a television cabinet with an antenna clip, constructed in accordance with the invention, securing an antenna to the cabinet.

FIGURE 4 is a partial top sectional view of the television cabinet of FIGURE 3 taken along line 4—4 of FIGURE 3, showing an antenna clip constructed in accordance with the invention securing an antenna to the cabinet.

Referring now to FIGURES 1 and 2, an antenna clip constructed in accordance with the invention is shown. In these figures a metal stamping is bent to form a pair of arms 10, an arm 11 and an arm 12, each extending from a base 13. The bent stamping is substantially cubical in shape. Each of arms 10 are stamped and bent at one end to form an inwardly extending rim 14 and outwardly extending teeth 15. Arm 11 has stamped in it an aperture 16, the rim of which is formed into a convex bearing surface 17. Arm 12 has stamped in it an aperture 18 and a smaller aperture 19. The angle

between base 13 and arms 10, arm 11 and arm 12 is slightly greater than 90° so that each of the two pairs of arms are outwardly biased.

FIGURES 3 and 4 show side and top sectional views of a television cabinet 20 to which is mounted an antenna 21. Television cabinet 20 has within it a cubical shaped enclosure having two oppositely disposed walls 22, a back 23, a wall 24 and a wall 25. In the drawing, back 23 and wall 24 are shown as being common with television cabinet 20, but it is understood that while this is a convenient method of incorporating the cubical enclosure within television cabinet 20, other geometries will be equally effective. An opening 28 is formed in wall 24, and an opening 30 is formed in wall 25 in registry with opening 28, a bearing collar 29 mounted within opening 28.

Antenna 21 comprises a spherical base 26 and concentric tubular antenna elements 27 passing through orifices in spherical base 26. A portion of the tubular antenna elements 27 is cut away in FIGURE 3 to better display the structure of the clip.

In mounting antenna 21 to television cabinet 20, spherical base 26 is positioned adjacent to bearing collar 29 with tubular antenna elements 27 passing through opening 28 and extending outside of television cabinet 20. While antenna 21 is being mounted, tubular antenna elements 27 are withdrawn so that no part of tubular antenna elements 27 extend below spherical base 26 into the interior of television cabinet 20. Walls 10 are bent towards one another by engaging rims 14 with a pliers or other suitable instrument. The clip is then pushed into the cubical enclosure until apertures 16 and 18 are in registry with openings 28 and 30 and wall 13 is in an abutting relationship with back 23. Convex bearing surface 17 is now adjacent to spherical base 26. The resiliency of the metal of the clip tends to force arm 11 towards wall 24, thereby frictionally securing spherical base 26 between bearing collar 29 and convex bearing surface 17. Arms 10 are then released and teeth 15 come into a "biting" engagement with walls 22, thereby insuring immobility of the clip. Spherical base 26 being thus positioned can undergo only limited rotational motion, which motion allows adjustment of antenna 21. The aforementioned alignment of apertures 16 and 18 with opening 28 and 30 allows tubular antenna elements 27 to be withdrawn into the interior of the television cabinet when antenna 21 is not in use.

Should it be desired to remove the clip, rims 14 are again engaged by a suitable instrument and drawn inwardly, thereby breaking the aforementioned biting engagement between teeth 15 and walls 22. The clip can then be withdrawn by merely pulling on rims 14 while maintaining the inward pressure on rims 14.

A lead 31 is passed through aperture 19, a conductive path being insured by soldering the lead to the clip. Lead 31 couples signals received by antenna 21 to the input of the television circuitry (not shown) in a well known manner.

What has been described is an antenna clip for mounting a rotatable antenna with a spherical base to a television cabinet, the clip comprising a first pair of resilient arms which cooperate with a first pair of oppositely disposed walls within the television cabinet to rotatably mount the antenna to the television receiver, and a second pair of resilient arms which cooperate with a second pair of oppositely disposed walls to insure immobility of the clip. While the invention has been described in the environment of a television cabinet to which is mounted a rotatable antenna with a spherical base, it is understood that this is merely for convenience in its description and the invention is not to be so limited. The invention is limited only by the appended claims.

The embodiments of the invention in which an exclusive property or privilege is claimed are defined as follows:

1. In combination with a receiver cabinet and a rotatable antenna, said receiver cabinet having an enclosure therein with a first and a second pair of oppositely disposed walls, one wall of said first pair of oppositely disposed walls defining an aperture therein, said rotatable antenna having a spherical base with an antenna element affixed thereto; an antenna clip for mounting said rotatable antenna to said receiver cabinet comprising: a base; first and second resilient arms affixed to said base; and gripping means affixed to said base independent of said first and second resilient arms; said first and second resilient arms cooperating with said first pair of oppositely disposed walls to rotatably position said spherical base between said first resilient arm and said one wall, said antenna element extending through said aperture in said one wall; said gripping means cooperating with said second pair of oppositely disposed walls to insure immobility of said antenna clip.

2. In combination with a television cabinet and a rotatable telescopic antenna, said television cabinet having an enclosure therein with a first and a second pair of oppositely disposed walls, said first pair of oppositely disposed walls defining respective openings in registration with each other, said rotatable telescopic antenna having a spherical base and concentric tubular antenna elements passing through orifices in said spherical base; an antenna clip for mounting said rotatable telescopic antenna to said television cabinet comprising: a base; first and second resilient arms each defining an aperture, said apertures being in registry with one another and with said openings; and gripping means affixed to said base independent of said first and second resilient arms; said first pair of oppositely disposed walls cooperating with said first and said second resilient arms to rotatably position said spherical base between said first resilient arm and one of said first pair of oppositely disposed walls, said concentric tubular antenna elements passing through said apertures and said openings, said gripping means cooperating with said second pair of oppositely disposed walls to render said antenna clip immovable therebetween.

3. In combination with a television cabinet and a rotatable telescopic antenna, said rotatable telescopic antenna having a spherical base and concentric tubular antenna elements extending through orifices in said spherical base, said television cabinet having an enclosure therein with a first and a second pair of oppositely disposed walls, said first pair of oppositely disposed walls defining openings in registration with each other, a bearing collar mounted in one of said openings, said spherical base being in seating engagement with said bearing collar; an antenna clip for maintaining said seating engagement comprising: a base; a first pair of resilient arms affixed to said base, said first pair of resilient arms defining apertures in registration with one another and with said openings; a convex bearing surface formed on the rim of one of said apertures; and gripping means affixed to said base independent of said first pair of resilient arms; said first pair of oppositely disposed walls cooperating with said first pair of resilient arms to rotatably position said spherical base in seating engagement with said bearing collar and said convex bearing surface, said concentric tubular antenna elements passing through said apertures and said openings; said gripping means cooperating with said second pair of oppositely disposed side walls to render said antenna clip immovable therebetween.

4. A combination as claimed in claim 3 wherein said gripping means comprise a second pair of resilient arms with biting surfaces thereon, said biting surfaces adapted

to bitingly engage said second pair of oppositely disposed walls.

5. An antenna clip for mounting a rotatable telescopic antenna to a television cabinet, said television cabinet containing a substantially cubical enclosure with a first and a second pair of oppositely disposed walls, said first pair of oppositely disposed walls defining a pair of openings in registry with one another, a bearing collar mounted in one of said pair of openings, said rotatable telescopic antenna having a spherical base defining a pair of diametrically opposed orifices, concentric tubular antenna elements being frictionally held within said orifices, said spherical base being in seating engagement with said bearing collar, means including said antenna clip maintaining said seating engagement; said antenna clip comprising: a rectangular base; a first and a second pair of oppositely disposed arms extending from said base, said first pair of oppositely disposed arms defining a pair of apertures in registry with one another, a convex bearing surface formed on the rim of one aperture of said pair of apertures, each of said second pair of oppositely disposed arms having an inwardly bent end and outwardly biased engaging means, said antenna clip being forcibly inserted within said enclosure such that said apertures are in registry with said openings and said spherical base is rotatably imprisoned between said bearing collar and said convex bearing surface, said outwardly biased engaging means frictionally engaging said second pair of oppositely disposed walls to insure immobility of said antenna clip, said inwardly bent ends being accessible to a suitable instrument for distending said second pair of oppositely disposed arms to break said frictional engagement and allow removal of said antenna clip from said enclosure.

6. An antenna clip as claimed in claim 5 wherein said engaging means comprise a serrated surface extending outwardly from said second pair of oppositely disposed arms, said serrated surface being in biting engagement with said second pair of oppositely disposed walls.

7. In combination; a television cabinet including a substantially cubical enclosure having top and bottom walls with openings therethrough and side walls; a telescopic rotatable antenna having a spherical base forming a pair of diametrically opposed openings therein and a plurality of telescopic antenna elements frictionally secured in said base; a bearing collar, dimensioned for rotatably retaining said spherical base, positioned in the opening in said top wall; a one piece box-like clip formed from resilient material having two pairs of oppositely disposed arms; one pair of said arms defining respective apertures in registration with each other; a bearing surface formed in the lip of one of said apertures, said spherical base being captured between said bearing surface and said bearing collar; and a plurality of outwardly disposed teeth in the remaining pair of arms for bitingly engaging said side walls, whereby said clip securely maintains said telescopic rotatable antenna within said television cabinet.

8. The combination set forth in claim 7 further including a pair of window-like extensions extending inwardly from said remaining pair of arms, said extensions enabling said remaining pair of arms to be flexed inwardly for removal of said clip.
